METHOD OF PRODUCING HOT CATHODE TUBES

Ellis Osmon Erickson, Pasadena, Calif., assignor
to Claude Neon Electrical Products Corpora-
tion, Ltd., Wilmington, Del., a corporation of
Delaware

Application May 10, 1932, Serial No. 610,454

3 Claims. (Cl. 176—2)

My invention relates to cathode discharge tubes, and has particular reference to a method of producing such tubes to exhaust the tube and to activate the filaments thereof.

5 In the manufacturing of luminous tubular lamps, particularly those employing one or more hot cathodes, characterized in the final operating condition by a cathode fall of potential of the order of the ionizing potential of the gas em-
ployed, it has been the practice to exhaust the
10 tube while the tube is heated by some exterior
means for the purpose of driving off gases oc-
cluded in the material from which the tube or
envelope is formed. The heating device has gen-
15 erally consisted of an oven in which the entire
tube will be placed and brought to a relatively
high temperature while the exhausting is taking
place. Such method is satisfactory for straight
20 lengths of tubing of which great numbers are to
be made in a standard or substantially standard
length.

When the tube is to be formed in various shapes
and configurations, and of varying length, the
25 construction of an oven which will be adapted for
various kinds and shapes of tubing becomes diffi-
cult, and the use of such an oven becomes incon-
venient and expensive.

It is, therefore, an object of my invention to
30 provide a method of processing hot cathode tubes
in which the entire process may be carried on in
the open, giving a full view of the tube, and in
which the tube is accessible to the operator at all
times and without discomfort to the operator.

Another object of the invention is to provide a
35 method of processing hot cathode tubes in which
the exhausting of the tube may be performed
without an exterior source of heat.

Another object of the invention is to provide
40 a method of processing hot cathode tubes in
which an electrical discharge is passed through
the tube while the pressure in the tube is at a low
value and is employed for heating the tube.

Another object of the invention is to provide
45 a method of processing hot cathode tubes which
are provided with a filament and activating ring
in which high potential is applied across the
rings to cause an electrical discharge therebe-
tween to raise the temperature of the tube.

Another object of the invention is to provide
50 a device for processing tubes in accordance with
my invention which is adapted to process tubes
of varying shapes and sizes without alteration
of any portion of the apparatus.

Other objects and advantages of my inven-
55 tion will be apparent from a study of the follow-

ing specifications, read in connection with the
accompanying drawing, wherein the sole figure
is a diagrammatic view of a complete set up of
apparatus required to process the tube in ac-
cordance with my invention.

5 Referring to the drawing, I have illustrated
a luminous tube 1 of the hot cathode type which
is to be employed with neon, argon, krypton,
helium, or other gas, or mixture of gases, which
will permit of operation with hot cathodes, such 10
tubes being known in the art as high intensity
luminous tubes. Such tubes usually comprise a
suitable envelope 2 which may be formed of glass,
quartz, or other suitable material having at each
15 end thereof electrodes, each of which comprises
a filament 3 supported upon stems 4 and 5
through which heating current may be conducted
through the filament to cause the temperature of
the same to be raised to bring the filament up
20 to high electron emission. Such tubes also em-
ploy a ring 6, preferably surrounding the filament
3, which ring is used during the processing of
the tube for the purpose of activating the fila-
ment. The ring 6 is illustrated as being sup-
25 ported upon a pair of stems 7 and 8, one of which
extends through the material of the envelope to
permit connection thereto of a suitable source of
electrical energy during the step of activating
the filament.

30 The electrode at the opposite end of the tube
is similarly constructed of a filament 9 mounted
upon stems 10 and 11, and the filament is sur-
rounded by a ring 12 mounted upon stems 13 and
14, one of which, like the stem 8, extends through
35 the envelope to permit electrical connection
thereto.

40 In the manufacture of such tube, the central
elongated portion 15 of the envelope may be
formed of the desired length and configuration,
while the end sections 16 and 17 may be assem-
bled with their filaments and rings and then
45 fused respectively to opposite ends of the cen-
tral section 15. An exhaust opening 18 is pro-
vided permitting the exhausting of gases from
within the completed envelope in finishing the
tube.

50 The assembled envelope and electrodes may
then be placed upon a suitable table 19, or other
support, and a vacuum pump may be connected
to the exhaust opening 18. When the air pres-
sure within the tube reaches a point of about
5 m. m. the occluded gases within the material
of the envelope should be driven out and to ac-
complish this result each of the activating rings
6 and 12 may be respectively connected to oppo-

site terminals of a suitable source of high potential electric current.

In the later steps of processing the tube a suitable heating current must be supplied to the 5 filaments 3 and 9, while direct current of relatively high potential must be applied to the activating rings 6 and 12.

I therefore provide a ready means for supplying various currents to the filaments of the electrodes through a multipole double-throw switch 20 connected in circuits which include a source of high potential alternating current (indicated by the legend 23000 V. A. C.) and also a suitable source of filament heating potential 21 for one 10 of the filaments, a similar source of heating potential 22 for the other filament, also a source of direct current relatively high potential 23 for one of the electrodes, and another 24 for the other of the electrodes.

20 By referring to the drawing, it will be observed that each of the electrodes has provision for the connection of three electrical conductors, namely, to each of the stems 4 and 5 for the filaments 3 and stem 8 for the activating ring 6. The electrode at the opposite end of the tube is also provided for connection of three electrical conductors, respectively, to the filament stems 10 and 11, and the activating ring stem 14. It is, therefore, desirable to select the switch 20 with six poles, 25 one for each of the conductors required to lead to the tube 1.

In order to facilitate the handling of the tube, I prefer to secure a terminal block 25 at some point adjacent the table 19, preferably at some 30 suitable height above the table to which may be connected a trio of flexible insulated conductors 26, 27 and 28. The conductor 26 is secured to

of the switch 20 are thus connected to the activating rings 6 and 12, respectively. Hence, by connecting the source of high potential alternating current to corresponding terminals of the switch 20 on one side thereof, closing of the switch 20 against these terminals will connect a suitably controlled high potential source to the activating rings 6 and 12. Hence when the pressure within the tube has been reduced to a low value, such as 5 m. m., supplying high potential 10 current to the rings 6 and 12, respectively, will cause an electrical discharge between these rings which will, in turn, cause a heating of the tube to any desired temperature. By regulating the current supplied to the rings with any suitable 15 control apparatus (not shown), the heating of the tube may be regulated. The value of current employed may range from 350 to 400 milliamperes, though different values may be selected for different types of material of which the envelope is made and for different diameters of tubing to be treated. If desired, the gas pressure in the tube 20 may also be suitably controlled to control the heating thereof.

I find that the best procedure includes that 25 of initially supplying the high potential current for a short period of time until the glass, or other material of which the envelope is constructed, has warmed up slightly. Then the current should be cut off and air be permitted to enter the tube 30 to again bring the pressure in the tube to atmospheric pressure. After this, the tube should again be exhausted to a low value, between 5 and 10 m. m. pressure. Then the discharge potential 35 may again be placed upon the rings to heat the tube.

At this time it will be found that the air pres-

5 terminal 61 is connected through a regulating rheostat 64 to one pole of a high potential source of current 23. With the switch 20 in position to contact terminals 53, 55, 54, 60, 61 and 62, the 10 filaments 3 and 9 are respectively heated, while high direct current potential is placed upon the rings 6 and 12. A discharge will occur between the ring 6 and its associated filament 3 to cause activation of the filament 3, as is well known in the processing or activating of filaments or cathodes in vacuum tube operation by bombardment of the cathode by positive ions.

15 During the discharge between the filaments and their associated rings, a blue haze will occur about the rings and filaments, which, as activation is completed and high vacuum conditions are approached, will disappear accompanied by a reddening of the ring elements by bombardment upon its surface by electrons coming from the 20 filament and now free to strike the rings with high kinetic energy by reason of the reduction in the number of gas particles present in the space which intervenes between filament and ring. The reduction in gas particles has resulted from the fact that the pump has been exhausting them and further because as the filament reaches complete activation, no further evolution of gases of decomposition of the coating takes place. Also, the gases occluded in the metal 25 of the filament and ring have been effectively removed when both of those elements reach red heat. If it is desired, the ring elements can be heated further by radio frequency induction, as is also well known in the art. Then the pressure 30 within the tube may be drawn down to any desired value, the proper amount of gas for producing the particular type of luminous tube desired being introduced to the tube, and the tube sealed, ready for use.

40 It will be observed that the rings 6 and 12 are primarily used for the purpose of activating the filaments and these rings are common in the construction of cathode discharge tubes. My process employs these same rings for the purpose of heating the entire tube, rendering it unnecessary for the tube to be placed in an oven or to be heated by any exterior device. Thus, irrespective of the shape or size of the tube, it may be readily treated without requiring any special construction of apparatus for various sizes and shapes of 45 tubes. Moreover, the entire processing of the tube occurs while the tube is accessible to an operator and once the connections between the switch 20 and the terminal of the tube are made, it is unnecessary to further handle the tube, and each step of the process takes place under the 50 eye of the operator, so that he may observe the condition of the tube at all times during the processing thereof, thus permitting a more ready production of uniform quality tubes.

55 My process of exhausting the tubes may also be applied to tubes designed for use with direct current in which one of the electrodes may be merely a plate or a carbon block, or similar device, in which case the electrode plate, block, or similar device, may be employed as the electrode at one end of the tube to which the high potential current may be supplied for the discharge of high potential current necessary for heating the 60 tube.

70 Also, my process is adaptable to tubes having cathodes of types other than filament type, particularly since most of these tubes are supplied with electrode assemblies at each end of the tube which include an electrode proper to be employed

in the normal operation of the finished lamp, and also employs shielding rings or similar devices so that the shielding rings, if present, may be employed as electrodes for the high potential bombardment of the glass of the lamp for the purpose of heating the same.

5

10 In certain types of tubes, the electrode which is to be used in the normal operation of the tube may be of such construction that the passage of electric current, necessary for the heating of the tube, would destroy or injure the electrode for later normal operation. In this event, it may be necessary to add to the electrode assembly a suitable high potential electrode structure, such as the activating ring illustrated in this application. Such ring, however, will not only serve the purpose of conducting the high potential current for the heating of the tube, but may also be formed about the normal electrode and be employed as a heat shield, if such shielding is later 20 desired in the normal operation of the tube.

15

25 The activation process herein set forth is particularly adapted to rapid processing of tubes, particularly tubes of the character in which the time consumed in activating the cathode or filament is not considerably great. In certain instances, wherein large cathode surfaces are to be activated, or wherein the cathode surfaces are slow to activate, the time consumed in activating the filament will permit the glass of the lamp 30 to cool off to a considerable extent and thus the gases which might be occluded in the filament, and which may be produced by the chemical changes occurring in the cathode structure during 35 activation, would tend to be absorbed by the now cooled glass. This condition may be avoided by passing high potential current between the electrode assemblies while the pressure within the tube is maintained at a relatively high value to 40 thus heat the glass, as hereinbefore described, then activating the filament as hereinbefore set forth, and then introducing into the tube a gas of such nature as will not chemically react with, or to "poison", the now activated surface 45 coatings of the electrodes to raise the pressure within the tube sufficiently to permit reheating of the glass upon passage of the high potential heating current.

30

50 Following this reheating of the glass, the tube is exhausted to high vacuum and the cathode parts are heated to drive off any occluded gases. Such parts as readily permit of such heating, such as filament type cathodes, are heated by supplying a heating current. Preferably, the positive 55 ion bombardment of the cathode surfaces is re-applied to assist in their complete degassification. In general, the activating ring elements will become heated to a red heat by electron bombardment in the latter stages of the positive ion bombardment of the cathode surfaces, as was described before. Additional heating of the ring elements can be produced by radio frequency induction, as is also well known in the art.

45

60 Immediately upon the reheating of the glass with the inert or nonchemically active gas there- 65 in, the condition of a hot glass, and hot activated electrode, is obtained so that the tube may be immediately evacuated to a high vacuum, the desired operating gases introduced into the tube, 70 and the same sealed off, thus completing the tube under the most favorable conditions.

65

75 While I have shown and described the preferred embodiment of my invention, I do not wish to be limited to the details of construction shown or

75

described herein, except as defined in the appended claims.

I claim:

- 5 1. In a device for processing hot cathode vacuum tubes having a pair of spaced cathodes each with an activating electrode adjacent thereto, a source of high potential electric current, a separate source of heating current for each of said cathodes, and a separate source of electrical potential for said activating electrodes, and means for selectively connecting said source of high potential in series relation with said activating electrodes and connecting said filaments and their activating electrodes, respectively, to their associated sources of current.
- 10 2. The method of processing hot cathode electrical discharge tubes having a coated cathode and having an activating electrode adjacent the cathode and another electrode at a point remote 15 from the cathode which includes the steps of (1) applying a high potential between the activating electrode and the remote electrode while maintaining sufficient gas pressure in the tube to produce a discharge capable of heating the envelope 20 of the tube to remove gas therefrom; (2) exhausting the tube to a very low pressure while applying potential between the cathode and its
- 15 25

adjacent activating electrode to activate the electrode; (3) introducing into the tube at sufficient pressure to support an envelope-heating discharge, a gas which is chemically inactive with respect to the activated cathode and again applying a high potential only between the activating electrode and the remote electrode to remove from the envelope any gas absorbed thereby during the activation of the cathode; (4) exhausting the tube while heating the cathode and activating the electrode, and (5) introducing the desired operating gas and sealing off the tube.

3. In the method of processing hot cathode electrical discharge tubes having a coated cathode requiring activation and having an activating electrode adjacent the cathode and another electrode remote therefrom which includes the steps of (1) exhausting the tube and activating the cathode; (2) introducing into the tube at sufficient pressure to support an envelope-heating discharge, a gas that is inactive with respect to the activated cathode and producing a discharge through said gas to heat the envelope, without poisoning the cathode, and (3) exhausting the tube while heating the cathode to eliminate gas 20 therefrom.

ELLIS OSMON ERICKSON.
